United States Patent Office

Des. 186,419
Patented Oct. 20, 1959

186,419

COMBINED ELECTRIC BROILER, GRILLE, AND TOASTER

Jack Keefe, St. Louis, Mo.

Application July 18, 1958, Serial No. 51,845

Term of patent 14 years

(Cl. D81—10)

Figure 1 is a perspective view of a combined electric broiler, grille and toaster, showing my new design.

Figure 2 is an elevational view taken from the right of Figure 1.

Figure 3 is a top plan view of Figure 1.

Figure 4 is an elevational view taken from the front of Figure 1.

I claim:

The ornamental design for a combined electric broiler, grille and toaster, as shown.
